Primary Examiner — Bao-Yen T Nguyen*Assistant Examiner* — Jessica Ruth Grable(74) *Attorney, Agent, or Firm* — Faegre Drinker Biddle & Reath LLP(57) **CLAIM**

The ornamental design for a capsule bed, as shown and described.

DESCRIPTION

FIG. 1 is a front perspective view of a capsule bed showing our new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The broken lines shown represent portions of the capsule bed and form no part of the claimed design.

1 Claim, 6 Drawing Sheets(56)
